V. SHEBAT

FLY AND BAIT AND LEADER HOLDER

Filed Sept. 10, 1924

UNITED STATES PATENT OFFICE.

VALENTINE SHEBAT, OF BUTTE, MONTANA.

FLY AND BAIT AND LEADER HOLDER.

Application filed September 10, 1924. Serial No. 736,927.

To all whom it may concern:

Be it known that I, VALENTINE SHEBAT, a citizen of the United States, residing at Butte, in the county of Silver Bow and State of Montana, have invented certain new and useful Improvements in Fly and Bait and Leader Holders, of which the following is a specification.

This invention has reference to holders or containers for fishing-tackle and more particularly to a novel fly and bait and leader holder.

An object of the invention is to provide a holder of the character and purpose set forth above which is of simple design and construction enabling it to be conveniently carried about, and providing separate compartments, access to each and all of which is readily had.

20 A further object of the invention is to provide a holder of the character described wherein the flies are adapted to be hooked onto a cork removably supported at one end of a tube, a cover of hingedly-connected parts being detachably engaged with the same end of the tube and extending over the cork for the protection of the flies.

Further objects and advantages of the invention may be apparent from the following 30 description of the device read in connection with the accompanying drawing, wherein:

Figure 1, is an elevation of the improved holder with a part broken away to disclose the round opening in the slide and cover of the bait compartment; Fig. 2 is a vertical central sectional view of the device; Figure 3, a top plan view of the slide and cover; Figure 4, a bottom plan view showing the hinged cover; Figure 5, a cross sectional view of the holder showing the compartments, and Figure 6, a detailed view of the wire for holding the hinged cover in place.

Describing the invention in detail, 10 designates the body of the holder which is preferably cylindrical and opened at both ends. A partition 11 divides the interior of the cylinder into a narrow compartment 12 and a larger compartment 13. The partition is flushed with the outer edge of the opening 50 at one end of the cylinder but at the opposite or bottom end of the cylinder the partition terminates a short distance inwardly of the opening as will be seen in Figure 2. This provides for the insertion of a cork 14 into 55 the bottom opening of the cylinder for closing the compartments at that end.

A flanged cap or cover 15 is removably engaged over the top of the cylinder and completely covers compartment 13. The cover is, however, provided with a small circular opening 16 so that access can be had to the larger compartment without removing the cap. Where the cap would normally extend across the small compartment 12, it is provided with an opening cut out as 60 indicated by dotted lines 17 of Figure 3 to provide an opening corresponding to the smaller compartment and this opening is normally closed by a slide 18 pivoted to cover 15, as shown at 19. Slide 18 is provided with a circular opening 20 corresponding to opening 16 of the cover, and as will be obvious access to compartment 13 is permitted only when openings 16 and 20 are in alignment. It will thus be seen that the 75 slide 18 provides a closure for both the smaller and larger compartments to open either of which it is necessary that the slide be rotated to uncover the compartment. In this connection, it is to be further noted that 80 slide 18 is cut away on one side of the pivot as indicated by the edge 21 so that when the slide is rotated half-way round edge 21 will coincide with the long edge 22 of opening 17, the latter being then uncovered. The larger 85 compartment 13 provides a receptacle for live bait such as grasshoppers, rockworms, salmon flies, angleworms, etc., which are placed in the compartment through the circular openings 16—20. The narrow compartment 12 provides a convenient receptacle for leaders and sinkers.

An elastic band 23 encircles the cylinder adjacent the top end and is used, as illustrated, to hold the leaders 24 of flies 25, the flies being hooked on the cork 14. By this arrangement it is possible to support a plurality of flies upon the cylinder and for the protection of the flies a hinged cover is provided at the bottom end of the cylinder for 100 engaging over and enclosing the flies. The hinged cover consists of two cover sections 26 and 27 having a common hinge 28 and being respectively flanged, as at 29, to engage over flies 25. The hinge 28 preferably 105 consists of a single strand of spring wire bent at opposite ends to provide clips 30 and 31 adapted to be engaged in sockets 32 on its opposite sides of cylinder 10. A spring 33 encircles the hinge 28 and has its opposite 110 ends engaged with cover sections 26 and 27 so as to normally retain the sections in closed

position. When it is desired to attach or remove a fly, one or both of the hinged sections can be swung back to uncover cork 14 or it can be entirely removed by simply withdrawing clips 30 and 31 from the sockets 32 of the cylinder. Cork 14 can also be withdrawn after removal of the hinged cover, so that the compartments can be easily emptied.

From the foregoing it will be seen that the invention provides a convenient and useful cylinder in which fishing-tackle can be safely carried and the fact that the two end covers are removable from the cylinder along with cork 14 enables the compartments to be fully and entirely opened at any time desired. Nor is the invention limited to the precise details of construction herein illustrated and described since various modifications and alterations in the arrangement, construction, and association of the various parts of the device, may be made in the scope of the appended claims.

Having thus described the invention, what I claim is:

1. A holder for fishing-tackle comprising a cylindrical body presenting separate compartments, an elastic member encircling the cylindrical body adjacent one end of the

holder, a cork closing the opposite end of the cylindrical body and providing a bottom for the said compartments, and a removable cover at each end of the said cylindrical body.

2. A fly and leader holder presenting a cylindrical body along the outside of which the leaders are adapted to be longitudinally disposed, a cork at one end of the said cylindrical body on which the flies are adapted to be hooked, an elastic member encircling the cylindrical body at the opposite end to hold the leaders of the said flies, and a hinged cover engaged with the cylindrical body and presenting separate sections adapted to engage over the said cork for the protection of the flies.

3. A holder comprising a cylindrical body presenting separate compartments, a cover at one end of the cylindrical body, a cork closing the other end of the cylindrical body, and a wire having its ends engaged in sockets on the said cylindrical body and extending across the said cork, and cover sections hingedly supported by the said wire, said hinged sections providing a cover for the said cork.

In testimony whereof I affix my signature.
VALENTINE SHEBAT.
